FUSE RECEPTACLE

George E. Wadsworth, Erlanger, Ky., assignor to
 The George B. Wadsworth Company, Cincinnati,
 Ohio, a corporation of Ohio

Application October 30, 1930, Serial No. 492,248

5 Claims. (Cl. 200—119)

My invention relates to fuse receptacles of the panel cut-out type.

The ordinary fuse, particularly for the plug type of cartridges, is susceptible of being circumvented by the insertion within the receptacle of a coin, a disc of metal or a piece of wire. This brings about a highly undesirable condition which is likely to cause fires, due to short circuiting of electrical apparatus in various parts of the establishment, and is also very likely to cause serious accidents, due to shocks which are received either during the attempt to insert the metal piece which is to circumvent the fuse, or because of current over-charging some of the electrical equipment which is supplied with current.

The ordinary plug fuse consists of a receptacle with a metal shell and with a central pin which the tip of the fuse is supposed to bear against. To replace an exhausted fuse, all that is necessary is to insert some metal piece within the plug socket which extends across between the central pin and the outer receptacle.

It is the object of my invention to provide a fuse receptacle in which no fuse other than the standard plug type of fuse can be employed. It is a further object to provide a receptacle in which electrical connection between the fuse and the contact members will not occur until such time as the plug fuse is completely screwed home.

Another object is the provision of a fuse receptacle in which the contact members are ordinarily dead until such time as the fuse is inserted.

Broadly, therefore, it is my object to provide a fuse receptacle in which nothing but an authorized fuse may be used and in which, regardless of an attempt to tamper with the receptacle and circumvent the fuse, no accident can be caused because until the fuse is inserted, the electrical contact members will not cause a shock.

The above objects and other objects to which reference will be made in the ensuing disclosure, I accomplish by that certain combination and arrangement of parts of which I have shown a preferred embodiment.

Referring to the drawings:—

Figure 1 is a perspective view of a panel cut-out fuse receptacle.

Figure 2 is a plan view of the fuse receptacle detached from the mounting cabinet.

Figure 3 is a sectional view taken along the lines 3—3 in Figure 2.

Figure 4 is a side elevation of the central spring contact pin.

Figure 5 is a perspective view of my cup-shaped insulating washer.

Figure 6 is a perspective view of a contact clip for the receptacle shell.

Figure 7 is a perspective view of the base contact plate. 60

Figure 8 is a perspective view of a receptacle shell.

Figure 9 is a sectional view taken along the lines 9—9 of Figure 10. 65

Figure 10 is a front elevation of the mounting cabinet on a slightly reduced scale from that shown in Figures 1 to 3.

Figure 11 is a bottom plan view of the receptacle and its mounting base, being taken from the bottom side of the view shown in Figure 2. 70

I have shown a panel composed of a pressed, open-front metal case 1, with a front panel 2 secured thereto and held in position as with screws 3. Openings 4 are provided in the sides of the case for the installation of the electrical conduits. A front cover 5 having an outwardly extending portion 6 is hinged to the front panel as with hinges 7. Openings 8 are further provided in the front panel through which the outer end of the fuse receptacles extend. 80

Referring now to the construction of the fuse receptacle itself, a mounting panel 9 of insulative material has annular extensions 10 preferably formed integral therewith. The annular members 10 have openings 11 through which the electrical contact plates may be extended. 85

The outer shells 12 are mounted on the panel within the annular members 10 by means of contact plates 13 and screws 14 extend up from recessed holes in the panel and engage threaded holes 15 in the contact members 13, thereby firmly securing the outer contact shells within the insulative annular members 10. The outer ends of the members 13 are provided with threaded holes 16 as shown in Fig. 6, which seat terminal screws 16a to which the wires of the circuit are ordinarily connected. 95

Within the contact shell there are mounted cup-shaped washers 17 composed of dielectric material, and the cup-shaped washers may be retained in position by extending the screws 14 through the apertures 18 in the panel 9 into tapped holes in the bases of the cup-shaped washers. 100

A contact plate 19 which fits within an opening 20 in the base of the panel, is connected by means of screws 21 to a plate 22 which carries a terminal screw 23 to which the line connection may be made. The plate 19 is, as indicated, 110

mounted in recessed position within the panel block and provides the electrical contact with the middle pins 24 against which the tips of the plug fuses contact. The pins 24, as indicated in Figure 3, have enlarged heads 25 which seat within recesses 26 which extend in from the recess 20. The pins also have enlarged contact heads 27 which are urged outwardly within the receptacle, as indicated in the upper receptacle 10 illustrated in Figure 3.

The lower receptacle indicated in Figure 3 shows the connections when a plug fuse is inserted. The plug fuse which I have indicated at 28 threadably engages the shell 12 and gradually 15 presses down on the pin 24 until when the lower end of the fuse is seated as far as it can be turned, the head 25 of the pin 24 will engage the contact plate 19 and thus permit the current to pass through the receptacle.

20 As an example of a double branch cut-out plug single fuse wiring diagram, we have indicated such an arrangement in Figures 2 and 3. The line wire, as indicated, extends to the screw 23 and the current passes down through the screws 25 21 and establishes a connection with the plate 19. The ground wire may be connected to a terminal screw 29 which threadably engages a metal plate 30 mounted on the base block with screws 31 which preferably are countersunk and 25 extend up from recessed holes from the lower side of the base of the block 9. The first and second circuits are supplied with current through wires which are connected to terminal screws 32 which are threaded into the plate 31.

35 It will thus be noted that in my construction I have provided a fuse receptacle which will meet with all the standard requirements of the Underwriter's specifications, in which the fuse receptacle is dead until such time as the standard 40 type of plug fuse is inserted into the receptacle.

Because of the washers 17 which have the cup-shaped annular sides, any flat piece of metal which it should be attempted to insert into the receptacle would be insulated from the outer shell by the time it was sufficiently depressed to contact with the plate 19. It will further be understood that while I have illustrated one particular type of fuse receptacle, various arrangements in which different circuit arrangements can be provided will readily occur to those skilled in the art employing the same principle of a normally out-of-contact middle spring pin.

If, in some modifications, the member 27 is 45 fixedly mounted and in direct contact with the plate 19, as long as the washer 17 has the annular skirt extending upwardly in the receptacle beyond the plane of the end of the pin, it will be impossible to insert a coin or washer in place of the regular shaped plug fuse. While such a construction will not have the contact parts dead 50 normally, the use of the washers will prevent unauthorized use of any other type of fuse in the receptacle than that for which the receptacle is intended.

Having thus described my invention, what I 55 claim as new and desire to secure by Letters Patent, is:—

1. In a receptacle comprising a threaded shell to receive a threaded connection member such as a fuse plug, with the threaded parts of the shell and member as connecting terminals, the connection member having a central contact element as

its other terminal, an insulating cup-shaped guard member fixed in the bottom of the receptacle and having a central aperture, a central contact element extending through said aperture and yieldingly mounted to recede toward the bottom of the guard member, said connection member central contact element contacting with the yieldingly mounted contact element when the connection member is screwed down into the receptacle and causing the recession of the yieldingly mounted element, and said receptacle comprising a base into which said yieldingly mounted element has an extension, and a contact member mounted in said base and contacted by the yieldingly contact element when the latter recedes, said guard member being deep enough to hinder direct connection of the yieldingly contact element and the receptacle shell by means other than the inserted connection member, without being so deep as to require special extension of the central contact element of said inserted connection member when the yieldingly contact element is in receded position.

2. A receptacle as set forth in claim 1, in which the receptacle shell has a bottom inturned part under the guard member, and in which the guard member and said shell are held in position by a fastening element passing up into the guard member from the receptacle base.

3. A receptacle as set forth in claim 1, in which the contact member mounted in the base is yielding to the receding contact member, and in which there is stop means at the bottom of the guard member, engaged by the central contact element of the inserted connection member to 105 positively limit the degree of passage of the latter member into the receptacle.

4. A receptacle as set forth in claim 1, in which the base has an upper and a lower space around the extension of the receding contact element, and in which the yielding mounting of the latter element consists of a spring mounted in the upper space, said extension having an enlargement in the lower space guidingly fitting said lower space and limiting upward protrusion of the receding 115 element by contact with the top of said space.

5. In a receptacle comprising a contact shell to receive in electrical contact the outer shell of an inserted connecting inserted device, which device also has a center contact element extending only 125 a slight distance past the inner end of its shell in proportion to the diameter of its shell, said receptacle having an aperture in its bottom, a relatively wide shallow annular guard lying close to the inner end portion of the receptacle contact 130 shell, and outstanding around said aperture, a center contact element for the receptacle extending through the aperture and the guard, to receive in electrical contact the center contact element of the inserted device, mounted to recede into the 135 guard under pressure of the inserted device, and contact means with which said center contact element of the receptacle is normally out of contact, but with which it makes contact when it recedes, said guard being of such depth as to allow substantially only the necessary inward movement of the inserted device to complete said contact before the outlying portions of the inserted device engages the rim of the guard, for the purposes set forth.

GEORGE E. WADSWORTH.
